HUMIDIFYING APPARATUS

Edward W. Bottum, Detroit, Mich., assignor to
 Skuttle Manufacturing Company, Detroit,
 Mich., a corporation of Michigan

Application June 13, 1946, Serial No. 676,559

2 Claims. (Cl. 126—350)

1

This invention relates to humidifiers of a character and arrangement of parts especially adapted for use with steam, hot air or hot water heating systems.

The object of the invention is to provide a new and unique arrangement of parts including a vapor generating unit by means of which moisture is discharged in the form of vapor into the atmosphere of a room and thereby prevents shrinkage of moisture absorbent articles in the room.

These and other features and objects of the invention are hereinafter more fully described and claimed and a humidifying apparatus embodying my invention is shown in the accompanying drawing which is a diagrammatic representation of the several parts of my improved humidifier apparatus.

In its preferred form the apparatus embodying my invention includes a hermetically sealed generator tube 1, which extends into the high temperature part of a furnace and on the other end of tube 1, which projects out of the furnace, is a jacket 2. The generator tube 1 contains a small charge 1a of a vaporizable material such as water and preferably the portion of tube 1, within the furnace, is inclined to the horizontal so that the charge runs to the lower end within the furnace. Tube 1 should preferably be evacuated when charged to remove air. The end of tube 1, exteriorly of the furnace is enclosed by jacket 2 which preferably is vertically positioned. The jacket 2 has an outlet 3 opening to a room exteriorly of the furnace and water is discharged to the jacket 2 by means of a conduit 4 opening at the bottom end of a settling tank 5. The settling tank 5 is provided with an opening in its bottom to which one end of the tube 6 opens and the opposite end of tube 6 opens to a chamber 7 provided by a cross wall 7a of a float tank 8. Within the float tank is a float 9, having an arm 11 which is pivotally supported on the outer side wall 10 of the tank by means of a bracket 9a and an adjustable element 11a provides for maintenance of a desired water level in the chamber between the partition 7a and the wall 10. A valve controlled inlet 7b has a threaded end 12 for connecting with a water supply conduit.

A metering wick 17, or series of such wicks depending upon the size of the apparatus, has the opposite ends thereof overlying the partition 7a. The wick or wicks function by capillary attraction to discharge water in limited amount per unit of time from the tank 8 through the tube

2

6 to the settling tank 5 and thence to the generator jacket 2. The wick may be made of any material having high capillary attraction such as fibers, ceramics, etc. Particularly satisfactory is a wick made of glass fibers sintered together and pressed while hot.

In operation, heat from the furnace quickly vaporizes the small charge in sealed tube 1. As the vaporized charge comes in contact with the 10 cooler portion of the tube enclosed by jacket 2, condensation takes place and the liquid charge is continuously running back tube 1 into the furnace to be revaporized. The temperature of the sealed tube 1 is considerably above the boiling point of water due to the fact that pressure within the tube will build up considerably above atmospheric pressure in the case of a water charge 1a. The thermodynamic properties of the charge of course govern the particular temperature-pressure relationship, but in the case 15 of a water charge it is normal for pressures within the tube to run as high as 50 lbs. per sq. inch and may run higher, depending upon the amount of charge considered consistent with safety requirements.

The float mechanism heretofore described serves to keep the portion of tank 5 between partition 7a and end 16 filled to a constant water level. The wick or wicks 17 through capillary action discharge a definite quantity of water per unit of time into the space 7, the water filling tube 6 and rising to partially fill settling tank 5. The temperature of settling tank 5 is kept sufficiently high to cause impurities to settle on the bottom of the tank, heat being transmitted from jacket 2 through conduit 4 by means of hot water or vapor.

Provision is made for cleaning out settling tank 5 to remove impurities when necessary. 40 This may be accomplished by removing cover 5a. Water from settling tank 5 flows into jacket 2 through conduit 4 as required and is vaporized by heat given off by the upper end portion of sealed tube 1. Vapor passes through the outlet 45 3 and is conducted through pipe or tubes to the space to be humidified or to a warm air plenum. The apparatus is automatic in its operation.

While I have shown and described the generator tube as extending into a furnace such as 50 is used in house heating systems it may be used in conjunction with other types of heating equipment and while I have termed the generating element 1, as a sealed tube, it may be of solid material such as a rod, its function being to transmit heat to the water or other vaporizable ma-

terial in the generator jacket 2. Metering wicks 17 and partition 7a could be entirely eliminated their only function being to supply the apparatus with water at a constant rate and thus prevent possible over humidification in some cases. However, the wicks and partitions could be eliminated if desired.

My improved humidifier provides several advantages heretofore not provided for.

(1) Through the wicks 17, a means is provided for controlling rate of humidification.

(2) The generator tube 1 requires only one hole for insertions into the furnace making for easy installation. It is not necessary to make any pipe connections within the furnace.

(3) It is impossible for leaks to develop into the furnace since no water is carried into the furnace under line pressure.

(4) Due to the small amount of charge to be heated, the apparatus responds very rapidly to cycling of the heating system and this is of particular advantage in intermittently fired systems.

It is believed evident from the foregoing description that my improved humidifying apparatus is comparatively simple and inexpensive in construction and functions automatically in supplying moisture to a confined space.

Having thus briefly described my invention, its utility and mode of operation, what I claim and desire to secure by Letters Patent of the United States is—

1. A humidifier for maintaining a desired moisture content in the atmosphere of an enclosed space which functions automatically to supply moisture to the atmosphere in accordance with temperature variations in the heating chamber of a furnace, said humidifier comprising a vapor generator jacket adapted to be disposed exteriorly of the furnace and having an opening to atmosphere, a sealed tube adapted to extend into said generator jacket and having one end adapted for insertion into the heating chamber of the furnace and means for metering a limited supply of water to said generator jacket comprising a tank connected with a source of supply, a valve for controlling flow of water to the tank, a float in the tank operatively associated with the valve for maintaining a constant level of

water in the tank, said tank having a transverse partition adjacent the end thereof, a wick positioned on the upper end of the partition and having its end portions on the respective opposite sides thereof whereby through capillary attraction water is caused to pass from the inlet side of the tank to the chamber provided by the partition and a conduit leading from said chamber to the jacket.

2. A humidifier for maintaining a desired moisture content in the atmosphere of an enclosed space which functions automatically to supply moisture to the atmosphere commensurate with the temperature variations within the heating chamber of a furnace, said humidifier comprising a vapor generator jacket having an opening to atmosphere, and means for supplying a limited quantity of water to said jacket and for preventing the accumulation of liquid water in said jacket including a heating means adapted to be heated by the furnace for conducting heat from the heating chamber to the generator jacket commensurate with the temperature in the heating chamber to vaporize and maintain the water within said generator jacket in a vapor state, a source of supply of liquid water adapted to be positioned externally of said heating chamber, and a wick for supplying the liquid water from said source of supply to said generator jacket by capillary attraction at a rate commensurate with the vaporization rate thereof by said heating means.

EDWARD W. BOTTUM.
